CLAIM

The ornamental design for the protective basketball display case as shown and described.

DESCRIPTION

FIG. 1 is a left back side top down perspective view of the protective basketball display case enclosing environmental subject matter.

FIG. 2 is a right back side top down perspective view thereof.

FIG. 3 is a front side view thereof.

FIG. 4 is a back side view thereof.

FIG. 5 is a left side view thereof. The right side view is a mirror image of the left side view.

FIG. 6 is a top down view thereof; and,

FIG. 7 is a bottom up view thereof.

Broken lines are used to illustrate portions of the protective basketball display case that form no part of the claimed design. The other broken lines illustrate environmental subject matter that form no part of the claimed design. With the exception of the magnets, the protective basketball display case, including edges thereof, are made of transparent material.
